UNITED STATES PATENT OFFICE.

EDRIC C. WARREN, OF JOHNSTOWN, PENNSYLVANIA, ASSIGNOR TO
CENTURY STOVE & MANUFACTURING COMPANY, OF JOHNSTOWN,
PENNSYLVANIA, A CORPORATION OF PENNSYLVANIA.

DESIGN FOR A STOVE.

SPECIFICATION forming part of Design No. 36,160, dated December 9, 1902.

Application filed October 17, 1902. Serial No. 127,743. Term of patent 7 years.

To all whom it may concern:

Be it known that I, EDRIC C. WARREN, a citizen of the United States, residing at Johnstown, in the county of Cambria and State of Pennsylvania, have invented a new, original, and ornamental Design for Stoves, of which the following is a specification, reference being had to the accompanying drawings, forming part thereof.

Figure 1 is a front elevation of a stove, showing my new design. Fig. 2 is a side elevation of the same.

As shown in the drawings, the characteristic and material features of my design consist of a frame A wider at the bottom or base in front and side elevation than at the top, having a curved or convex door of lattice formation, having an ornamental scroll B ex-

tending across the lower part of the door and from the upper to the lower edge thereof at 20 the center, an ornamental plate C extending from the top at the rear thereof, and brackets D D extending from the sides, the inner edges of which and the front top sides and the ornamental plate are highly ornamental, with 25 interlacing scrolls E, as shown.

Having described my invention, what I claim as new, and desire to secure by Letters Patent, is—

The ornamental design for a stove, as herein 30 shown and described.

EDRIC C. WARREN.
